UNITED STATES PATENT OFFICE.

MARTIN CHRISTENSEN, OF RACINE, WISCONSIN, ASSIGNOR TO CHRISTENSEN MACHINE COMPANY, OF RACINE, WISCONSIN, A CORPORATION OF WISCONSIN.

SIGNATURE-HANDLING DEVICE.

1,335,221.

Specification of Letters Patent. Patented Mar. 30, 1920.

Application filed May 11, 1918. Serial No. 233,951.

To all whom it may concern:

Be it known that I, MARTIN CHRISTENSEN, a citizen of the United States, and resident of Racine, in the county of Racine and State 5 of Wisconsin, have invented new and useful Improvements in Signature-Handling Devices, of which the following is a description, reference being had to the accompanying drawings, which are a part of this specification.

The invention relates to signature handling devices and more particularly to a feed table and its associated mechanism whereby the groups of signatures may be 15 fed to the machine by a plurality of operators.

The invention is designed to provide a book-feeding table in which the books are disposed in radial guides so that a plurality 20 of operators may serve the table and dispose the groups of signatures in the radial guides from which they are carried into the machine, the arrangement increasing the working capacity of the individual operator with 25 the result that the capacity of the book-stitching machine is greatly increased because of the rapidity of feed of the collected groups of signatures to the mechanism for feeding the books to the stitchers.

30 The invention is further designed to provide new and useful improvements in the construction of feed table shown in Letters Patent No. 1,297,444, issued to me March 18, 1919, the improvements being in the provisions for adjusting the table for different 35 sizes of books and in varying the feed or operation of the table and for alining the signatures.

The invention further consists in the several features hereinafter set forth and more particularly defined by the claims at the conclusion hereof.

In the drawings:

Figure 1 is a plan view of the device embodying the invention, parts being broken away;

Fig. 2 is a section taken on the line 2—2 of Fig. 1;

Fig. 3 is a fragmentary detail view of the means for turning the table; and

Fig. 4 is a fragmentary detail view of the means for alining the signatures.

In general the device comprises a receiving table, means for intermittently turning 55 the table, and means for successively deliv-

ering collected groups of signatures from the table to the book-stitching machine. With reference to the means for successively delivering collected groups of signatures from the table to the book-stitching 60 machine, a part which is designated generally by the numeral 3, attention is directed to Letters Patent No. 1,297,444, previously referred to, which shows the means for successively delivering the signatures from the 65 table to the book-stitching machine, and as the subject matter of the present invention is directed more particularly to the construction of the receiving table, further reference to the means for taking the signatures from the receiving table and delivering 70 them to the machine is deemed unnecessary.

The receiving table consists of a circular base 4 being centrally secured to a member 75 5 carried by a central post 6, which post is journaled in a frame 7, having brackets 8 to which receiving aprons 9 are secured to lie flush with the base 4 and at a quadrant's distance from each other. The receiving 80 table further consists of a plurality of radially disposed partitions or guide members 10 having outer tapered ends 11, and forming radially disposed pockets. In addition to the partitions 10 mounted upon the base 85 4, supplemental partitions 13 of corresponding shape are disposed in adjustable spaced relation to the partitions 10 by means of their connection through brackets 14 to a spider 15 which is adjustably mounted upon 90 the post 6 by means of a threaded hub 16 for the spider engaging the threaded end 17 of the post 6. Thus the partitions 13 are mounted in spaced relation with respect to the partitions 10 and are moved toward or 95 away from the partitions 10 depending upon the breadth of the signatures being handled. The partitions 13 may be spaced nearer to or farther away from the partitions 10 by revolving the spider 15 upon the 100 post 6 in the proper direction. Thus the partitions 10 and 13 form spaced guides for radially disposed signatures upon the base 4.

In placing the signatures upon the table means are provided for limiting the position to which the signatures may be moved inwardly in the guides, and this is accomplished by means of adjustable back stops, one for each pocket. Each of these back stops consists of an angled plate 18, the 110

lower portion 19 of which is provided with a plurality of apertures 20 to receive pins 21, which pins not only pass through one of the apertures 20, but may also be inserted in sets of radially alined spaced apart apertures 22, there being a set of apertures 22 to take care of each back stop.

With the construction thus far described, the operators stationed adjacent the aprons 10 9 place the groups of signatures into the pockets 12 between the guides 10 and 13, pushing them in until the front edges of the signatures abut against the upper portion 23 of the back stop 18, the adjustment of the 15 back stops being made so as to permit the front portion 24 of the signatures to extend beyond the table a short distance to be engaged by the previously referred to mechanism for successively delivering the signatures from the receiving table to the stitching machine. Thus with this construction the adjustment of the back stops and the adjustment of the partitions 10 and 13 with respect to each other will readily accommodate books of various sizes.

The means for intermittently turning the table to successively present the groups of signatures to the machine is similar to that of my Letters Patent previously referred to 30 in that it consists of a ratchet wheel 24 formed on the member 6 and engaged by a pawl 25 mounted upon a lever 26 which is oscillated by a reciprocating rod 27, but the means for controlling the pawl is different.

35 In this construction the means for controlling the pawl consists of a cam 28 journaled on the lever 26 coöperating with a cam roller 29 carried by the pawl 25, and further comprises means for intermittently rotating the cam 28 when desired, it being noted that the cam is provided with recesses 30 and projections 31 so that when the roller 29 is in any one of the recesses 30 the pawl 25 is held in engagement with one of the teeth of the 45 ratchet 24, so that when the cam 28 is turned to bring the projection 31 against the roller 29, the pawl will be moved outwardly out of engagement with the ratchet wheel 24.

Unless the cam 28 is turned it will hold 50 the pawl 25 in the position to engage the ratchet wheel 24 and the forward movement of the rod 27 will cause the pawl to move the ratchet wheel one tooth thus turning the table a partial revolution and then on the 55 backward movement of the pawl the table will remain at rest. Thus continued reciprocation of the rod 27 causes a step by step rotary movement of the table which is timed to bring one group of signatures adjacent 60 the feed fingers 3' of the feeder mechanism to the book-stitching machine and during the period of rest of the table the group of signatures presented to the machine are engaged by the fingers 3' and drawn into the 65 machine as explained in my Letters Patent

previously referred to. However, in book-stitching machines for practical purposes the strokes of the feed fingers are limited and in the case of a group of signatures of considerable length it is necessary to stop the feed of the table so that the feed fingers 3' may twice engage the signatures presented to them and remove them in two operations to the stitching machine.

To provide for permitting two operations 75 of the feed fingers 3' in the case of long books or groups of signatures I have devised a means for stopping the rotary movement of the table on alternate forward movements of the rod 27 and this is accomplished by 80 mechanism which rotates the cam 28 so that for every other forward movement of the rod 27 the cam 28 will be turned so that one of its projections 31 moves the pawl 25 out of operative engagement with the ratchet 85 wheel 24.

This mechanism for operating the cam 28 consists of a spring pressed pawl 32 mounted on the bracket 33 which bracket is adjustably secured to the table 7 by means of 90 a bolt 34, said bracket adapted to be turned so as to abut against the stop 35 or the stop 36. The cam 28 carries a ratchet wheel forward by a plurality of circumferentially arranged pins 37. The pawl 32 is normally held against a stop pin 38 by a spring 39. When the bracket 33 is turned about the bolt 34 so that it abuts against the stop 35 as shown in Fig. 1 the pawl 32 will be in inoperative position and the cam 28 will be 100 operated as previously described to impart a step by step rotation to the table during every reciprocation of the rod 27. When the bracket 33 is turned about the bolt 34 so that it abuts against the stop 36 then the pawl 32 is moved into the path of the pins 37 of the cam 28 and under these conditions on the first forward movement of the rod 27 the pawl 25 being held by the cam 28 will turn the ratchet wheel 24 the distance 110 of one tooth and the pawl 32 moves in between two of the pins 37. On the first rearward movement of the rod 27 the pawl 32 strikes one of these pins 37 and turns the cam 28 so as to move the roller 29 out of one 115 of the depressions 30 and on to one of the projections 31, thus throwing out the pawl which is held out on the next forward movement of the rod 27 so that no movement is imparted to the table, and on the next rearward movement the pawl 32 strikes the next pin 37 and the cam 28 is turned to bring the roller 29 into one of the depressions 30 and thus permit the pawl 25 to again engage 120 the ratchet 24. Thus on every other reciprocation of the rod 27 no movement is imparted to the table and this is used where the book is too long for the stroke of the feeder.

The turning movement of the table is ar- 130

rested by a band brake 40 and brake wheel 41 which is more specifically shown and described in the Letters Patent before referred to.

5 The means for alining the signatures while they are on the table consists of an angled rod 42 carried by a collar 43 which in turn is adjustably secured to the rod 27. The collar 43 is so set on the rod as to permit the 10 rod 42 to strike against the rear edges of the signatures on the rearward movement of the rod 27 as shown in Fig. 1 thus pushing the signatures against the back stop to aline them. The adjustment of the collar 15 43 with respect to the rod 27 provides for handling groups of signatures of different lengths.

The construction above described thus embodies a table which will readily accommodate books of different sizes, a means for imparting either a step by step rotary movement to the table on every reciprocation of the rod 27 or upon every other reciprocation of said rod and also a means for alining the signatures while on the table.

I am aware that the specific details of construction herein shown and described are capable of some modification and change, and I therefore desire it to be understood 30 that such changes as come within the scope of the appended claims are within the spirit of my invention.

What I claim as my invention is:

1. In a signature handling mechanism, the 35 combination with a table, of a plurality of signature receiving pockets thereon, adjustable back-stops for the pockets, a plurality of guideways disposed above the table and registering with said pockets, and 40 means for adjustably supporting the guideways at various heights above the table.

2. In a signature handling mechanism, the combination, with a table, of a plurality of 45 radially disposed guide members mounted thereon to form radially disposed signature receiving pockets, a plurality of radially disposed supplemental guide members adapted to be brought into line with the guide members on the table, and means for adjustably 50 supporting said supplemental guide members at various heights above the table.

3. In a signature handling mechanism, the combination with a table provided with 55 signature receiving pockets, of means for intermittently turning the said table including a reciprocating rod, and a member mounted on said rod and moved thereby into engagement with one of the edges of a group

of signatures to aline them while on the table, and back stops forming the ends of 60 said pockets and against which the other edges of said signatures abut.

4. In a signature handling mechanism, the combination with a table provided with a plurality of signature receiving pockets, of 65 means for intermittently turning said table including a reciprocating rod, and means operated by said rod and engaging the outer edges of the signatures to aline the same.

5. In a signature handling mechanism, the 70 combination of a revoluble table provided with a plurality of radially disposed signature receiving pockets, means for normally imparting a step by step rotary movement to said table, and means for rendering said 75 first named means inoperative during every other normal cycle of operation.

6. In a signature handling mechanism, the combination of a revoluble table provided with a plurality of signature receiving 80 pockets, means for normally imparting a step by step rotary movement to the table, and means for automatically rendering said first mentioned means operative only at pre-determined intervals to vary the normal 85 rotary movement of the table.

7. In a signature handling mechanism, the combination of a revoluble table provided with a plurality of radially disposed pockets, pawl and ratchet mechanism for 90 normally imparting a step by step rotary movement to said table, tripping mechanism for the pawl to vary the normal rotary movement of the table, and means actuated by said pawl and ratchet mechanism for 95 operating said tripping mechanism.

8. In a signature handling mechanism, the combination with a rotary feed table, pawl and ratchet mechanism for normally imparting a step by step rotary movement to 100 said table, a pawl tripping cam, and means for rotating said cam to trip the pawl and thereby vary the normal rotary movement of the table.

9. In a signature handling mechanism, the 105 combination with a table adapted to receive groups of signatures, of means for turning the table including a rod, and a signature alining member adjustably mounted on said rod and moved thereby to selectively engage the groups of signatures carried by the table to aline the same.

In testimony whereof, I affix my signature.

MARTIN CHRISTENSEN.
